UNITED STATES PATENT OFFICE.

THOMAS HENRY WARD, OF TIPTON, COUNTY OF STAFFORD, ENGLAND.

VALVE FOR STEAM-ENGINES.

SPECIFICATION forming part of Letters Patent No 338,004, dated March 16, 1886.

Application filed July 26, 1883. Serial No. 101,967. (No model.) Patented in England June 16, 1882, No. 2,848; in France June 26, 1882, No. 149,773; in Germany June 26, 1882, No. 23,403, and in Belgium July 3, 1882, No. 58,373.

To all whom it may concern:

Be it known that I, THOMAS HENRY WARD, a subject of the Queen of Great Britain and Ireland, and a resident of Tipton, county of Stafford, England, have invented certain Improvements in Valves for Steam-Engines, (for which I have obtained British Letters Patent No. 2,848, dated June 16, 1882; French Patent No. 149,773, dated June 26, 1882; Belgian Patent No. 58,373, dated July 3, 1882, and German Patent No. 23,403, dated June 26, 1882,) of which the following is a specification.

My invention consists of certain improvements in the construction of the steam-chests and valves of steam-engines, designed with the view of economizing room, saving metal, and providing a convenient and economical arrangement of parts, as fully described herein-after.

In the accompanying drawings, Figures 1 and 2 are sections, taken at right angles to each other, showing my present invention applied to a compound tandem-engine, such as described in my British Patent No. 4,672 of 1881. Figs. 3 and 4 are sectional views of the high and low pressure cylinders on opposite sides of the intermediate casting, and both looking toward the latter. Fig. 5 is a sectional plan view through the valve-chest, and Fig. 6 is an enlarged sectional view showing some of the steam-ports.

The valves in my present invention are equilibrium slide-valves, and where they are applied to compound tandem-engines such as shown, they are arranged on each side of the casting which separates the high and low pressure cylinders. I form the inlet and outlet ports, covered by the said valves, in the shape of the letter H, as illustrated in Fig. 1 and by dotted lines in Figs. 3 and 4, so that the valves themselves may have a corresponding form. The recessed parts leave convenient spaces for the exhaust-passages p for carrying the exhaust-steam from the steam-space below the covers C out into the exhaust-pipe E, and also leave convenient spaces for the bolts p' , which connect the said covers C, as shown more fully in Fig. 2. Room is thus economized and metal saved, and a convenient and economical construction provided.

The slide-valves P are connected together by

a cross-pin, p^2 , through which passes a rod, p^3 , extending on each side (in the case of twin valves which command the ports of compound engines) through tubes or passages q , Figs. 1 and 5, forming conduits for the steam from the steam-inlet chamber A past the various passages to the small chamber r on each side. In these steam-chambers r slide piston-valves or plungers p^4 , fixed to the respective ends of the said rod p^3 , to which the slide-valves P are attached.

In the steam-engine described in my aforesaid British patent, the slide-valves are shown and described as being operated mechanically; but in the present case I have shown them as being adapted to be operated by steam by destroying the equilibrium of the pressure of steam on the piston-valves p^4 . The following is a convenient way of carrying this into effect: In connection with each chamber r is a second steam-chamber, s , (shown more fully in Fig. 7,) provided with a piston-valve, t , on the same rod with a beat-valve, t^2 , which in its normal position is pressed to its seat by a spring, t^3 . Each chamber r communicates through a bypass, r^2 , with the chamber s —that is to say, that part of it which constitutes the space between the piston-valve and the beat-valve t^2 . Leading from the chamber s^4 , at the outer side of this beat-valve t^2 , is a passage, s^2 , communicating between the said chamber s^4 and one or other of the ports of the high-pressure cylinder, Fig. 1. The inner side of the piston-valve t is open to the chamber s^3 , with which communicates a pipe, u , in communication with passages u^2 from the respective ends of the high-pressure cylinder, Figs. 1 and 4.

It should be understood that the constructions described are in duplicate—one on one side of the casting for operating the slide-valves P in one direction, and that on the other side of the casting for moving the said valves in the opposite direction—as shown in Figs. 1 and 5.

In the construction described the inlet-steam passes in opposite directions through the tubes q into the opposite steam-chambers, r , in which the piston-valves p^4 operate, and the steam leaks through a small passage or passages in or around the said valves to the other sides thereof, so that these valves are kept in equilibrium.

When steam is admitted on one side of the

working-piston, as soon as the piston has completed or nearly completed its stroke a portion of the steam enters by the passage u^2 and pipe u , Figs. 1 and 4, to the steam-chamber s^3 on one side and forces the piston-valve t therein back. The beat-valve t^2 is therefore caused to open so that the steam in the chamber r behind the piston-valve p^4 passes through the by-pass r^2 into the chamber s and out by the passage s^2 . Thus the steam escapes more rapidly than steam can leak through or past the piston-valve p^4 , so that the equilibrium is destroyed, and these piston-valves are consequently moved and shift the slide-valves P to admit steam to the other side of the pistons of the steam-cylinders. The same operation takes place on the other side of the valve-actuating device, and so on alternately, so that the slide-valves are actuated by the relief of steam-pressure alternately from one and the other of the chambers r . In order to relieve the pressure from these chambers r by hand, to move the slide-valves, when required, a passage, w , is provided from each chamber r to the outside, as more fully illustrated in Fig. 7. This passage w is normally closed by a valve, w^2 , which valve is attached to a spring-rod, w^3 , extending to the outside. When one of these rods is pushed inward, the steam behind the

piston-valve p^4 can escape through a space or spiral groove around the rod w^3 of the valve w^2 , so that the slide-valves may be caused to move in one direction or the other independently of the passages from the steam-cylinders.

I wish it to be understood, however, that I do not claim in this application the devices for operating the slide-valves by steam, since, so far as my present invention is concerned, they may be operated mechanically; but I have described the steam operation as the method preferred and for the better understanding of my invention.

I claim as my invention—

The combination of the valve chest having steam-ports of **H** form, and slide-valves having corresponding form, with covers C , central exhaust-pipe, E , and exhaust-passages p in the recesses left between the said ports, substantially as specified.

In testimony whereof I have signed my name to this specification in the presence of two subscribing witnesses.

THOMAS HENRY WARD. [L. S.]
